DOUBLE PARALLEL SPRAY BAR

Henry R. Erickson, Minneapolis, Minn.

Application May 7, 1941, Serial No. 392,231

10 Claims. (Cl. 299—34)

This invention relates to road spraying devices and more particularly to improvements in spray bars.

One of the objects of my invention is to provide a spray bar construction which is made up of at least two relatively movable sections wherein the sections in one position thereof are in alignment and serve as a continuous straight bar and wherein one bar section can be swung relative to the other to place the sections parallel to each other in tandem to provide a double spray bar where one section lies beside the other.

A more specific object of the invention is to provide a central relatively stationary spray bar section and movable sections at each end of the central section, the movable sections being each half the length of the central section and swingable from positions aligned with the central section to positions parallel thereto, whereby one movable section can be swung parallel to half of the central section in order to double the amount of surfacing material on a portion of a strip being sprayed and to spray the remainder of the strip with an ordinary normal application.

A further object of the invention is to provide a spray bar as set forth above which is constructed to circulate liquid from an inlet conduit throughout the entire lengths of all sections of the spray bar and to return the liquids or at least a portion thereof to a common outlet conduit and also to provide means for permitting such circulation regardless of the position to which either of the movable sections is swung.

Another object of the invention is to provide a spray bar of the type set forth in the preceding paragraph with spray outlet valve controls permitting opening or closing of the valves in each section and in different portions of the central stationary section regardless of the positions of the movable sections.

Still a further object of the invention is to provide a movable connection between the stationary section and a movable section which is offset from said sections when they are aligned and which permits circulation of liquid through said connection at all times regardless of the position to which the movable section is set.

Another object of the invention is to provide means for balancing pressures in various parts of the spray bar to insure uniformity of discharge through various discharge outlets.

Still a further object of the invention is to provide valved spray outlets wherein the valves are effectively prevented from freezing, and wherein

the valves are so constructed as to increase ease of operation thereof.

Another object of the invention is to provide means for introducing emulsified liquids to the spray bar which will prevent the emulsion from separating when a supply tank has been emptied and a new supply is thereafter directed to the spray bar.

These and other objects and advantages of the invention will more fully appear from the following description made in connection with the accompanying drawings, wherein like reference characters refer to the same parts throughout the views, and, in which:

15 Fig. 1 is a more or less diagrammatic rear elevation of a wheeled vehicle having my road spraying apparatus mounted thereon;

20 Fig. 2 is a plan view of my improved spray bar assembly showing alternate full line positions of the movable sections and intermediate dotted line positions of one of said sections;

25 Fig. 3 is a fragmentary longitudinal vertical section through approximately half of a spray bar assembly;

30 Fig. 4 is an enlarged transverse section through a portion of the spray bar;

Fig. 5 is an enlarged vertical section through the transfer turret connecting relatively movable sections and taken approximately on the line 5—5 of Fig. 2;

35 Fig. 6 is an enlarged section taken approximately on the line 6—6 of Fig. 2;

Figs. 7 and 8 are horizontal sections through the fluid transfer turret and taken approximately 40 at the levels indicated by lines 7—7 and 8—8 in Fig. 6; however, the assembly in Fig. 6 shows the spray bar sections parallel whereas in Figs. 7 and 8, said sections are moved into longitudinal alignment; and

45 Fig. 9 is a more or less diagrammatic view through a portion of the fluid transfer turret taken approximately on the line 9—9 of Fig. 2.

In Fig. 1 there is shown a vehicle having wheels 10 and a frame 11. A liquid supply tank 12 is supported by the frame 11 and said tank has a spray bar inlet pipe 13 and a spray bar outlet pipe 14 connected thereto. The pipe 13 has a suitable liquid pump 15 connected therein as well as an adjustable flow valve 16. The spray bar outlet pipe 14 has a control valve 17 connected therein and the portion 14a of said outlet pipe lies around the spray bar inlet pipe 13 concentrically thereto.

The spray bar proper includes a central relatively stationary section 18 and a pair of rela-

tively movable sections 19. Said central spray bar section 18 has an opening 20 formed in its central upper portion and the spray bar outlet pipe 14a communicates with the upper inner portion of said central spray bar section 18, as best shown in Fig. 3. Extending longitudinally of the interior of the spray bar section 18 is a transverse partition 21 which divides the spray bar into a lower inlet chamber 22 and an upper outlet chamber 23. The spray bar inlet pipe 13 extends through the partition 21 and terminates in the spray bar inlet chamber 22. There is no communication between the spray bar inlet pipe 13 and the upper outlet chamber 23. If desired, a sump 24 with a drain plug 24a may be provided below the spray bar inlet pipe 13 in the lower central portion of the spray bar section 18.

Each of the movable spray bar sections 19 is provided with a longitudinal partition 21a which divides said movable sections into lower inlet chambers 22a and upper outlet chambers 23a. The partition 21a as will be seen in Fig. 3 terminates short of the end cap 19a to permit the flow of liquid around the end of partition 21a to the upper outlet chamber 23a.

The central spray bar section 18 and its movable sections 19 are provided with a plurality of outlet nozzles 25 which, as best shown in Fig. 4, are threaded into sleeves 26 which extend upwardly from the bottoms of said sections through the longitudinal partition 21 to the upper spray bar outlet chamber 23. (Fig. 4 is described as applied to the central spray bar section 18 but is also typical of one of the movable sections 19.) The sleeve 26 has a branch 27 within which is formed a frusto-conical bore 28, the latter receiving a frusto-conical valve core 29. The core 29 is retained by a combined spacer sleeve and washer 30 and nut 31 which lie around a valve core rod 32. Each of the rods 32 carries a lever 33 which is pivotally connected at 34 to an elongated valve operating rod 35.

A feature of the spray outlet valves should be noted. The valve cores 29, as best shown in Fig. 4, have their smaller ends exposed to liquid under pressure in the lower chambers of the spray bar sections. This produces an endwise thrust upon said cores 29 tending to press them toward the larger ends of the valve casing bores 28. Consequently, the cores 29 will not tend to jam in said frusto-conical bores 28 and the valves will at all times operate with greater freedom.

There is a valve operating rod 35 for each of the movable spray bar sections 19. The central spray bar section 18 has two such operating rods 35, each of which is connected to a group of half of the spray outlet valves in said central section. Each of said central bar section operating rods 35 has a rod 36 connected thereto by a universal joint 37 and the opposite end of the rod 36 is connected by a universal connection 38 to a lever 39. Lever 39 is mounted for rotation with a vertical shaft 40 which, as best indicated in Figs. 1 and 3, rises upwardly and has a manual operating handle 41 connected thereto, said handle being located conveniently adjacent the rear portion of the liquid supply tank 12 on the vehicle.

The movable spray bar sections 19 each have their valve operating rods 35 connected by universal joints 42 to links 43, and the opposite end of each of said links 43 is connected by a universal joint 44 to a flexible cable 45. The flexible cable 45 is positioned in a flexible sheath 46 and the opposite end of said cable 45 is connected by a universal joint 47 to a link 48 which

in turn is connected to a lever 49 mounted for movement with a vertically disposed shaft 50 similar to the shaft 40 previously described. On the upper end of the vertical shaft 50 is a hand operated lever 51. Mounted adjacent the ends of the central spray bar section 18 and also upon the movable sections 19 are flexible cable guides 52 adjacent the ends of each of the cables 45.

In Fig. 5 there is shown a liquid transfer turret 10 T which permits the flow of liquid from one spray bar section to the other and return and which also provides a pivotal connection between the stationary central spray bar section 18 and the movable sections 19. The outer ends of the central spray bar section 18 are provided with rearwardly extending lower offset conduits 53. Liquid flows from the inlet pipe 13 into the lower central spray bar chamber 18 and thence into the offset 53. The flow from the offset thence goes rearwardly, as viewed in Fig. 5, past the walls 54 and 55 and upwardly into the central chamber 56 formed in the sleeve-like member 57, which has a partition 58 forming chamber 56 and an upper chamber 59. The liquid then flows downwardly through a collar 60 out of the lower cage 61 to a lateral offset conduit 62 which is connected to the movable spray bar section 19 and has flow communication with the lower chamber 22a. It will be seen that the arrow leading from the passage 53 to the chamber 56 is dotted intermediate its ends. This indicates that the liquid flows upwardly and to the rear of that structure through which the dotted line passes, there being an opening provided for such flow.

After the liquid has traveled to the end of a movable section 19 through the chamber 22a it returns through the chamber 23a to an offset conduit 62a and thence through the upper cage 61a to the upper portion 59 of the sleeve-like member 57. From the chamber 59 the flow is as indicated by the upper arrow with a central dotted portion, said dotted portion indicating flow upwardly and behind the structure through which it passes. This brings the liquid to the upper left-hand offset conduit 53a from whence it flows to the upper fluid outlet chamber 23 in the main spray bar section 18.

Figs. 7 and 8 which are taken approximately on the lines 7-7 and 8-8 of Fig. 6 (the spray bar sections being parallel in Fig. 6 and opened up into alignment in Figs. 7 and 8) show certain portions of the turret flow conduits. The stationary spray bar sections are shown at 18, and in Fig. 8 the upper spray bar outlet chamber 23 is shown. The movable spray bar sections 19 are illustrated.

As best indicated in Fig. 9 the sleeve-like member 57 is a portion of the casting which includes the offset conduits 53 and 53a. The sleeve-like member 57 has an opening 63 which is the opening through which the liquid flows from the offset 53 to the chamber 56 and said sleeve-like member has an opening 63a through which liquid flows from the chamber 59 to the upper offset conduit 53a. This is the flow indicated by the partially dotted arrows of Fig. 5. The openings 64 and 64a are openings through the walls 54 and 54a which together with the open cages 61 and 61a permit the flow of liquid into and out of said cages.

Referring back to Figs. 7 and 8 there is shown the upper offset conduit 53a connected to the stationary bar section 18 and the offset conduit 62a which is in communication with the movable spray bar sections 19.

When the device is assembled the casting comprising the offset conduits 58, 58a and its attached sleeve portion 57 receive extensions of offset conduits 62, 62a above and below said sleeve-like portion 57. The collars 60 and 60a are threaded into the ends of the sleeve 57 and packing rings 65 are then placed in position. Against these packing rings are placed the inner edges of the cages 61 and 61a. The caps 66 are then threaded into suitable threaded openings in the casting which includes the offset conduits 62 and 62a. The nutted bolts 67 are threaded through the caps 66 to permit pressing of the two cages 61 and 61a against the packing rings 65. Lock nuts 68 secure the bolts 67 in position. The upper bolt 67, as shown in Fig. 5, carries a small shouldered stud 69 beneath the head of which is positioned a swivel member 70. The member 70 serves as a support for the intermediate portion of the flexible cable 45 connected between the main spray bar section 18 and the movable section 19.

Because of the fact that the spray bar outlet nozzles 25 communicate with the upper or fluid return chambers 23 and 23a of the spray bar sections and partially obstruct the fluid inlet chambers 22 and 22a there might be sufficient drop in pressure adjacent the beginning of the fluid return pipe 14a to affect the evenness of distribution of surfacing material and if such a drop took place there would be less liquid issuing from the nozzles adjacent the center of the central spray bar section than at the outer ends of the movable sections. For this reason I have connected a pipe 71 between the lower main bar section inlet chamber 22 adjacent the lower end of the fluid supply pipe 13 and have connected the other end of the pipe 71 with the upper main spray bar chamber 23 at a point preferably adjacent the outer end of said section 18. Thus pressure is transmitted nearly directly to the upper main spray bar chamber 23 to supplement any drop in pressure occasioned by the travel of the liquid through the fluid transfer turret and pivot and to the end of each movable section 19 past and around all of the outlet sleeves 26. The pipe 71 has a flow control valve 72 positioned therein.

Connected to the vertical spray bar return pipe 14a is a bracket 73 having a substantially horizontal portion 73a upon which the ends of the movable spray bar sections 19 may rest when they are swung in in the manner shown at the left-hand side of Fig. 2. When said movable sections 19 are swung out into alignment with the central spray bar section 18, as shown in the right-hand side of Fig. 2, a pivoted spring pressed lever 74 snaps over a catch 75 to keep the movable section 19 in its aligned position.

When the pump 15 is actuated to supply liquid from the tank 12 to the fluid supply line 13, said fluid is conveyed to the lower chamber of the main spray bar portion 18 and thence in opposite directions to the ends of the main spray bar section 18. From there the fluid passes through the fluid transfer turret and pivot T to the lower chambers 22a of the movable spray bar sections 19. After passing around the ends of the partitions 21a in said movable spray bar sections the fluid is directed toward the center of the central spray bar section. In its passage liquid is supplied to the various valved spray outlets and nozzles 25 and a portion of this flow is carried through the upper half of the liquid transfer turret T to the upper or return chamber 23 of 75

the main spray bar section 18. From there the excess liquid passes up the vertical return pipe 14a to the tank 12.

It should be noted that regardless of the positions to which the movable spray bar sections 19 are swung the spray outlet valves in said movable sections can be opened or closed. These outlet valves in the main spray bar section 18 are divided into two groups which can also be opened or closed at will. With the apparatus in the position shown in full lines in Fig. 2 it will be possible when spraying a road to spray a double quantity of liquid along a portion of the road such as adjacent the shoulder and simultaneously produce a normal spray throughout the remainder of the spray bar unit.

The pump 15 may be considered as being any suitable type of reversible pump or if a reversible valve is used in the supply line 13 liquid may be reversed in the distributing system and in that event the spray bar can be emptied to the point where the upper chambers 23 and 23a in the spray bar sections are empty, thus preventing the dripping of surfacing fluid from the spray outlets and still the lower chambers 22 and 22a in said spray bar sections may remain comparatively full. In the use of asphaltic emulsions and the like it is desirable, of course, that the emulsion not be broken down. If the tank should need refilling the upper chambers of the spray bar sections could be emptied by reversing the flow and when the tank has been refilled the flow can be again directed downwardly through the supply pipe 13 and there is little likelihood of breaking down the emulsion. This is due to the fact that the emulsion is not agitated to any appreciable extent as it would be if it were pumped into a completely empty spray bar.

It will, of course, be understood that various changes may be made in the form, details, arrangement and proportions of the various parts without departing from the scope of my invention.

What is claimed is:

1. In road spraying apparatus and the like, a relatively stationary spray bar section, a relatively movable spray bar section, said spray bar sections being longitudinally divided to provide inlet and outlet chambers therein, a pivot element connecting said spray bar sections, and said pivot element having a pair of fluid conduits therein, one of said conduits being in communication with the inlet chambers of said spray bar sections in all positions of said relatively movable section, and said pivot element having a fluid conduit therein in communication with said outlet chambers in all positions of said relatively movable spray bar section.

2. In road spraying apparatus and the like, a spray bar having an inlet chamber and an outlet chamber, a fluid supply connection with said inlet chamber, said chambers having flow communication at a point remote from said supply inlet, said outlet chamber having a return connection communicating therewith at a point remote from the communication between said chambers, said spray bar having spray nozzles communicating with said outlet chamber, and pressure equalizing means in said chambers comprising a conduit connecting said inlet chamber with said outlet chamber at a point spaced from said first mentioned communication between said chambers.

3. The structure in claim 2 and said pressure

equalizing means providing flow communication between said inlet chamber and said outlet chamber at a point between the outlet connection of said outlet chamber and the first mentioned point of communication between said chambers.

4. The structure in claim 2 and said pressure balancing means comprising a conduit extending from said inlet chamber to said outlet chamber at a point adjacent the outlet connection of said outlet chamber.

5. In road spraying apparatus and the like, a spray bar having a fluid inlet and an outlet, a plurality of spray nozzles at spaced points along said spray bar between said inlet and outlet, and a pressure balancing fluid inlet conduit connected to said spray bar between said first mentioned fluid inlet and said outlet.

6. The structure in claim 5 and said pressure balancing fluid inlet conduit being connected to said spray bar adjacent said outlet.

7. In road spraying apparatus and the like, a longitudinally divided relatively stationary spray bar section having an inlet chamber and an outlet chamber in fluid flow communication, a longitudinally divided relatively movable spray bar section having an inlet chamber and an outlet chamber in flow communication, said inlet chamber being in flow communication and said outlet chambers being in flow communication with each

other, said relatively movable section in one position, being substantially in longitudinal alignment with said relatively stationary section, and in another position, said relatively movable spray bar section lying substantially parallel to said relatively stationary section.

8. The structure in claim 7 and the flow communication between said inlet chambers and the flow communication between said outlet chambers being maintained in both positions of said spray bar sections.

9. The structure in claim 7 and said spray bar sections having outlets therein, valves controlling the flow through said outlets, and a common actuator for the valves in said relatively movable section, said actuator being movable in both positions of said relatively movable spray bar section.

10. In a road spraying apparatus and the like, an elongated spray bar section, a fluid inlet conduit connected to said spray bar section and adapted to convey fluid to said spray bar section, said spray bar section having a return conduit, and a bypass conduit connected to said fluid inlet conduit and also connected to said spray bar section between the points of connection of said inlet conduit and said return conduit with said spray bar section.

HENRY R. ERICKSON.
